UNITED STATES PATENT OFFICE.

HAWKINS R. MARTIN, OF FORT WORTH, TEXAS.

CONVERTIBLE FURNITURE.

Application filed October 15, 1923. Serial No. 668,683.

To all whom it may concern:

Be it known that I, HAWKINS R. MARTIN, a citizen of the United States, residing at Fort Worth, in the county of Tarrant and State of Texas, have invented certain new and useful Improvements in Convertible Furniture, of which the following is a specification.

This invention relates to convertible furniture, more particularly to a portable bed swing, and has for its object to provide, in a manner as hereinafter set forth, an article of such class which can be quickly converted from a swing into a bed or vice versa, and which includes a series of adjustable suspension elements for securely suspending the article when converted into a swing or into a bed at the desired height with respect to the ground or the floor of a room.

Further objects of the invention are to provide in a manner as hereinafter set forth, a portable bed swing, which is simple in its construction and arrangement, unusually strong and durable, compact, including a resilient body portion, thoroughly efficient in its use, readily converted from a swing into a bed or from a bed into a swing, quickly assembled and inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a perspective view of a convertible article of furniture in accordance with this invention, showing the article in swing form.

Figure 2 is a rear elevation of Figure 1.

Figure 3 is a fragmentary view, broken away, showing the article extended in the form of a bed.

Figure 4 is a fragmentary view illustrating a modified form of connecting a suspension element with the frame of the article.

A convertible article of furniture, in accordance with this invention, which is a portable bed swing, comprises a sectional frame, a resilient body portion and two sets of sus-

pension elements. The frame members constituting the sectional frame can be formed from pipes, I-beams, channel irons and angle bars, but preferably the frame members are constructed of angle bars and the sectional frame of the article is illustrated as being constructed from angle bars.

The sectional frame is formed of two sections one referred to generally by the reference character A and the other by the reference character B. The section A comprises a pair of spaced opposed longitudinally extending front and rear angle bars 1, 2, and a pair of horizontally disposed end angle bars 3, 4, which are mounted upon the bars 1, 2, inwardly with respect to the ends of these latter, whereby the bars 1, 2, will project from the bars 3, 4. The vertical legs of the bars 3 are mounted on edge on the bars 1, 2, and the horizontally disposed legs of the bars 3, 4, extend inwardly with respect to the vertical legs and with the horizontal leg of the bar 3 projecting towards the horizontal leg of the bar 4.

Fixedly secured to the bar 1, as well as the bar 2, at a point removed from each end of each of said bars, is a vertically disposed supporting bracket 5, and abutting against said brackets 5, as well as being secured thereto by the hold-fast devices 6, are the end bars 3 and 4. The horizontal legs of the end bars 3, 4, are seated upon the upper edges of the brackets 5. Hold-fast devices 7 are employed for fixedly securing the brackets 5 upon the horizontally disposed legs of the bars 1 and 2.

The horizontally disposed leg of each of the bars 1, 2, outwardly with respect to the bars 3, 4, has fixedly secured therewith a vertically disposed hook member 8, and the said members 8 are arranged exteriorly with respect to the vertical legs of the bars 3 and 4.

The section B consists of a pair of horizontally disposed angle-shaped end bars 9, 10, and a longitudinally extending angle bar 11 upon which one end of each of the bars 9 and 10 is mounted and secured by a supporting bracket similar in construction and arrangement to the bracket 5. The bar 11 projects from the bars 9, 10, and the projecting end thereof is provided with a hook member 12 similar in form to the hook member 8. The hook members 12 are arranged exteriorly of the bars 9 and 10. The bars 9 and 10 are set up with respect to the bar 11 in the same manner as the bars 3 and 4 are set up with respect to the bars 1 and 2 and

so that the horizontal legs of the bars 9 and 10 will extend inwardly from the vertical legs of said bars and with the horizontal leg of the bar 9 extending towards the horizontal leg of the bar 10.

When the sections A and B are shifted to provide a bed, the vertical legs of the bars 3 and 4 align with the vertical legs of the bars 9 and 10 and the horizontal legs of the bars 10 3 and 4 align with the horizontal legs of the bars 9 and 10.

The section B is hinged to the section A, and the means for hinging the two sections together consists of a pair of sectional leaf 15 hinges. One section of each of the hinges is indicated at 13 and the other section of each of the hinges is indicated at 14. The sections 13 are fixedly secured to the upper face of the horizontal legs of the bars 3 and 4, 20 and the sections 14 are fixedly secured to the upper face of the horizontal legs of the bars 9 and 10. Hold-fast devices 15 are employed for fixedly securing the sections 13 to the bars 3 and 4, and hold-fast devices 16 25 are employed for fixedly securing the sections 14 to the bars 9 and 10.

The resilient body portion of the article of furniture is formed of two sections, and one section is carried by the section A of the frame and the other section of the body portion is carried by the section B of the frame. Each section of the body portion consists of a series of longitudinally extending suitably spaced slats 17 and a longitudinally extending slat 18 which is of greater width than either of the slats 17. The slats 17 and 18 are connected together by a series of resilient elements 19, disposed transversely of the slats, and said elements 19 have one end connected to the inner slat 17 and the other end to the slat 18 which is arranged outwardly with respect to the series of slats 17. Each of the resilient elements comprises a plurality of spaced coils which are interposed 40 between the slats. The resilient elements 19 are furthermore secured to the inner slats 17, as at 20.

That section of the body portion which is carried by the section A of the frame, has 50 each of its slats 17, at each end thereof, connected to a coiled spring 21. The springs 21, at one end of the slats 17, are connected to the horizontal leg of the bar 3, and the springs 21 at the other end of the slats 17 55 are connected to the horizontal leg of the bar 4. The slat 18 of that section of the body portion which is carried by the frame A, has one end connected with the horizontal leg of the bar 3 by a pair of coiled springs 60 22, and its other end connected with the horizontal leg of the bar 4 by a pair of coiled springs 23.

The slats 17 of that section of the body portion carried by the section B of the frame, has one end connected by coiled 65

springs 24 to the horizontal leg of the bar 9, and the other end connected to the horizontal leg of the bar 10 by coiled springs 25. The slat 18 of that section of the body portion carried by the section B of the frame, is 70 connected at one end to the horizontal leg of the bar 9 by a pair of coiled springs 26, and at its other end to the horizontal leg of the bar 10 by a pair of coiled springs 27.

The bar 2 of the frame A, has a depressed 75 intermediate portion 28, to provide a clearance for the resilient body portion when the latter is forced downward by the weight of the body of the person reclining or sitting thereon, and by the setting up of the bar 2 80 with the depressed portion 28, the resilient body portion will not contact with the bar when depressed on the application of pressure thereto.

Two sets of suspension elements are employed for the purpose of suspendingly supporting the article when set up in the form of a swing or in the form of a bed, and preferably the suspension elements of each set are in the form of a chain. The suspension elements of each set are indicated at 29, 30 and 31. The lower ends of the elements 30 and 31 are adjustably connected to the hook members carried by the ends of the bars 1 and 2 of the frame A. The lower 95 end of the suspension element 29 of each set is provided with a snap hook 32, which can be adjustably connected to the element 29 and which furthermore is attached to a hook member 12.

When the article is set up in the form of a swing, as shown in Figure 1, the hook members 12 project forwardly from the bar 11, but when the article is in the form of a bed, the hook members are disposed vertically 105 with respect to the bar 11.

In Figure 4 of the drawings, a flexible suspension element is illustrated at 33, and is in the form of a chain and is connected by a coupling member 34, attached to a link 110 35 engaging with the hook member 36, and this form of connection between the suspension 33 and the hook member can be employed if desired.

It is obvious that the sections A and B 115 can be provided with any suitable means for detachably securing them in the position as shown in Figure 3, although such means is not necessary, as the weight of the frame sections A and B will maintain the same 120 extended in the form of a bed.

Although the preferred embodiment of a portable bed swing, in accordance with this invention, is as illustrated and described, yet it is to be understood that changes in the 125 details of construction can be had which fall within the light of the invention as claimed.

What I claim is:—

1. In combination, front, back and inter- 130

- mediate longitudinally extending inverted angle bars arranged in spaced relation, two opposed pair of horizontally extending end bars of angle contour, the bars of each pair having their inner ends opposing each other, the forward end bar of each pair having the ends of its vertical leg seating on edge on the top of the horizontal leg of the front and intermediate bars inwardly of an end thereof, the rear end bar of each pair having the ends of its vertical leg seating on edge on the top of the horizontal leg of the back bar inwardly of an end thereof, means secured on the horizontal legs of each pair of end bars for hinging the inner ends thereof together and for supporting the inner end of the rear bar of the pair, means for securing the forward bar of each pair to the front and intermediate bars, means for securing the outer end of the rear bar of each pair to said back bar, said intermediate bar having the major portion of its length depressed below the planes of the front and back bars, and suspension means extending through the horizontal legs of said front, back and intermediate bars outwardly with respect to the ends of said pairs of end bars.
2. In combination, front, back and intermediate longitudinally extending inverted angle bars arranged in spaced relation, two opposed pair of horizontally extending end bars of angle contour, the bars of each pair having their inner ends opposing each other, the forward end bar of each pair having the ends of its vertical leg seating on edge on the top of the horizontal leg of the front and intermediate bars inwardly of an end thereof, the rear end bar of each pair having the outer end of its vertical leg seated on edge on the top of the horizontal leg of the back bar inwardly of an end thereof, means secured on the horizontal legs of each pair of end bars for hinging the inner ends thereof together and for supporting the inner end of the rear bar of the pair, means for securing the forward bar of each pair to the front and intermediate bars, and means for securing the outer end of the rear bar of each pair to said back bar, said intermediate bar having the major portion of its length depressed below the planes of the front and back bars.
3. In combination, front, back and intermediate longitudinally extending inverted angle bars arranged in spaced relation, two opposed pair of horizontally extending end bars of angle contour, the bars of each pair having their inner ends opposing each other, the forward end bar of each pair having the ends of its vertical leg seating on edge on the top of the horizontal leg of the front and intermediate bars inwardly of an end thereof, the rear end bar of each pair having the outer end of its vertical leg seated on edge on the top of the horizontal leg of the back bar inwardly of an end thereof, means secured on the horizontal legs of each pair of end bars for hinging the inner ends thereof together and for supporting the inner end of the rear bar of the pair, means for securing the forward bar of each pair to the front and intermediate bars, means for securing the outer end of the rear bar of each pair to said back bar, said intermediate bar having the major portion of its length depressed below the planes of the front and back bars.

In testimony whereof, I affix my signature hereto.

HAWKINS R. MARTIN.
